WIRE CONNECTOR

Arden L. Van Nest, Oak Park, Ill., assignor to
 Western Electric Company, Incorporated, New
 York, N. Y., a corporation of New York

Application January 13, 1939, Serial No. 250,695

2 Claims. (Cl. 287—78)

This invention relates to wire connectors, and more particularly to connectors for splicing and dead-ending telephone wires.

An object of the invention is to provide a simple and inexpensive connector by which a reliable electrical and/or mechanical connection between two or more wires may readily be made.

In accordance with the above object, one embodiment of the invention contemplates the provision of a connector for splicing bridle wires to telephone line wires, the connector comprising a longitudinally grooved soft copper core and a tubular shell surrounding the core and cooperating with the grooves thereof to provide separate wire receiving bores adapted to be contracted into intimate contact with the line and bridle wires.

Other features, advantages and adaptations of the invention will become apparent from the following detailed description when read in conjunction with the accompanying drawing, in which

Fig. 1 is a plan view showing how the connector may be used for connecting a bridle wire to a telephone line wire, and for dead-ending line wires;

Fig. 2 is an enlarged transverse sectional view taken on line 2—2 of Fig. 1;

Fig. 3 is an enlarged transverse sectional view taken on line 3—3 of Fig. 1;

Fig. 4 is a longitudinal sectional view taken on line 4—4 of Fig. 3;

Figs. 5 and 6 are perspective views of the inner core and shell, respectively, of the wire connector shown in Figs. 3 and 4, and

Fig. 7 shows the inner core and shell assembled together and ready to be used, for example, for connecting a bridle wire to a telephone line wire.

Referring now to the drawing, one form of wire connector embodying the invention is shown in Fig. 7, wherein it is designated generally by the numeral 10. It comprises a substantially cylindrical core 11 encased in a tubular shell 12. The core is preferably composed of soft metal, such as annealed copper, and is formed with two longitudinally extending wire receiving grooves 13 and 14, as best shown in Fig. 5. The shell 12 preferably comprises a seamless tube of copper or other suitable metal.

The core is inserted into the shell and the latter is then rolled or otherwise compressed into intimate contact with the core, as shown in Fig. 7. The interior surface of the shell thus cooperates with the grooves 13 and 14 to provide separate bores for receiving the wires to be spliced

or joined. Obviously, the size and cross-sectional shape of the grooves 13 and 14 may be varied to accommodate wires of various sizes and shapes, and if desired, the core may be provided with more than two wire receiving grooves in order to accommodate more than two wires. Also, the relative positions of the grooves with respect to each other may be varied, as desired. Furthermore, the improved wire connector may be of one-piece construction, although the two-piece core and shell construction is cheaper and equally satisfactory.

Fig. 1 illustrates how the wire connector 10 may be used to advantage for splicing a bridle wire 16 to a dead end 17 of a telephone line wire 18. It will be noted that one of the two wire receiving bores of this connector is just large enough to receive the line wire, while the other wire receiving bore is relatively smaller for receiving the relatively smaller bridle wire. In making the splice, the dead end 17 of the line wire is inserted through the larger bore of the connector and the bare end of the bridle wire is inserted in the smaller bore. The connector 10 is then rolled or otherwise compressed into intimate contact with the bridle and line wires, thus making a reliable gas tight electrical connection therebetween.

As further illustrated in Fig. 1, a connector 20 of the type embodying the invention may be used to advantage for dead-ending telephone line wires. The connector 20, like connector 10, comprises a cylindrical core 21 (Fig. 2) encased in a tubular outer shell 22, but the two wire receiving bores of connector 20 are of the same size. When employing the connector for dead-ending a telephone line wire, as shown in Fig. 1, the end portion of the line wire is first inserted through one of the wire receiving bores of the connector 20 and then looped around a dead end support 25, after which it is inserted in the other wire receiving bore of the connector. The connector is then rolled or otherwise compressed into intimate clamping contact with the adjacent parallel portions of the line wire and its end, thus making a firm, reliable dead-end joint.

It is to be understood that the invention is not limited to the specific embodiments thereof herein illustrated and described, but is capable of other adaptations within the scope of the appended claims.

What is claimed is:

1. A wire connector comprising an inner soft metal core having a plurality of longitudinally extending grooves in its outer surface, and an

outer soft metal shell completely surrounding the core and compressed into intimate contact therewith, the inner surface of said shell cooperating with said grooves to provide a plurality of separated wire received bores, said core and shell adapted to be simultaneously compressed into intimate contact with wires in said bores to provide a gas tight electrical connection therebetween.

2. An electrical connector for connecting separate electrical conducting wires, comprising a core formed of soft conducting metal provided with longitudinal wire receiving grooves and a 5 close fitting cylindrical shell formed of soft metal completely surrounding the core, said core and shell adapted to be simultaneously compressed upon the wires within the core grooves.
